SILO ROOF STRUCTURE

William W. Gurney, Winona, Minn., assignor to
Madison Silo Company, Madison, Wis.

Application August 2, 1939, Serial No. 288,051

3 Claims. (Cl. 108—32)

This invention appertains to new and useful improvements in roof structures for silos and the like.

The principal object of the invention is to provide a silo roof of dome shape constructed of a plurality of interconnecting sector-shaped sections.

Another important object of the invention is to provide a silo roof construction wherein the parts can be preformed readily at the manufacturing plant and subsequently assembled without any definite degree of skill on the part of workmen, on the job.

These and other important objects and advantages of the invention will become apparent to the reader of the following specification.

In the drawings:

Figure 1 represents a top plan view of the roof.

Figure 2 is a section on the line 2—2 of Figure 1.

Figure 3 is a section on the line 3—3 of Figure 1.

Figure 4 is a fragmentary detailed sectional view showing the tie rod anchoring means.

Figure 5 is a fragmentary inside elevational view of the lower portion of the roof at one of the ribs.

Figure 6 is a fragmentary detailed sectional view on the line 6—6 of Figure 5.

Figure 7 is a fragmentary side elevational view of the roof at the doorway.

Figure 8 is a fragmentary horizontal sectional view taken substantially on the line 8—8 of Figure 7.

Figure 9 is a fragmentary detailed sectional view taken substantially on the line 9—9 of Figure 7.

Figure 10 is a sectional view taken substantially on the line 10—10 of Figure 7.

Figure 11 is a section substantially on the line 11—11 of Figure 3.

Referring to the drawings wherein like numerals designate like parts, it can be seen that the roof is generally constructed of the roof proper 5, dome 6 and cap 7. The roof proper 5 is constructed of a plurality of sectors which will be alternately referred to by reference characters 8 and 9. The sectors 8 and 9 are connected together by rib structures such as is shown in Figure 2. Each rib structure consists of the elongated longitudinally arcuate-shaped outside channel member 10 and the inside channel member 11. Each sector 9 has one edge portion bent inwardly and backwardly as at 12 to define a channel in which the inturned edge portion 13

of the clip strip 14 is disposed. This clip 14 embraces the outwardly curved edge portion 15 of the outside channel member 10 and fits snugly against one side flange of the channelled member 10 as shown in Figure 2. The inside channel member 11 has side wing portions 16, one of which bears against the innermost portion of the clip 14 while the other wing member 16 is embraced by the clip strip 17. This clip strip 17 has the inwardly bent edge portion 18 which engages into the channel defined by the inwardly and backwardly bent adjacent edge portion 19 of the corresponding panel 8 (see Figure 2). The adjacent edge of the channel member 10 has the outstanding flange 20 which bears against the outside of the adjacent edge portion of the panel 8 to hold the same snugly against the in-turned edge portion 18 of the clip strip 17. To hold these parts all in firmly clamped position a tapered screw 21 is disposed through the outside channel member 10 at desired intervals and screwed into a corresponding opening of the inside channelled member 11. This action of the screw 21 draws the channelled members 10 and 11 together and causes the parts aforescribed to firmly bind or clamp together.

As shown in Figures 5 and 6 and again in Figure 4, a tie rod 22 provided with a turnbuckle or the like (not shown) extends around the lower portion of the roof part 5 where the latter overlaps the concrete side wall structure 23 of the silo (not shown).

This tie rod 22 extends through the slots 24 in the lower portion of the rib structure aforescribed and which will be generally referred to by A. Thus with the tie member 22 disposed through the slot 24 the lower portion of the part 5 of the roof will be held against the silo wall structure 23. Hook bolts 25 as shown in Figure 6 are hooked over the tie rod 22 and the threaded shank portion is disposed through openings in the channel members 10 and 11. Nuts 26 on the threaded shank at the inner and outer sides of the channelled members 10 and 11 serve to properly fix the hook bolt to the rib structure 10. As shown in Figure 4, a hook bolt 27 embraces the tie member 22 and has its shank 28 disposed through an opening in the wall structure 23 of the silo so as to prevent any tendency of the roof to lift in the event of high winds. The shank 28 is equipped with a nut or other detent 29.

As shown in Figure 1, angle bars 30 can be secured in position across a pair of adjacent rib

structures A to form a ladder over the part 5 of the roof.

As shown in Figure 3, the upper edge portion of the roof part 5 extends against the vertical flange a of an angle iron annulus 31. Tie bolts 32 extend upwardly through the base of this annulus 31 and through the panels 8 and 9 and also through the dome structure 33. The upper ends of the bolts 32 are equipped with wing nuts 34 which can be fed downwardly against the dome 33 to firmly hold the dome in place upon the upper edge of the annulus 31. The dome 33 is of frustro-conical shape and has radially disposed corrugations 35.

15 A conical-shaped cap member 36 is disposed over the upper portion of the dome 35 and is suitably secured in place. Suitable rivets or the like can be employed for securing the structure part 5 of the roof directly to the annulus 31.

20 The sliding door structure is as illustrated in Figures 7, 8, 9 and 10. As can be seen in Figures 1 and 7, one of the panels 8 is shortened and is identified as panel 8a. Parallel guide rib structures generally referred to by reference characters B—B are secured at their upper portions by the binding plates 37 to the adjacent rib structures A. As before stated these rib structures B—B are parallel disposed and are intended to define guideways for the upper and lower slide doors 38 and 39. Between each of the rib structures B and the adjacent rib structure A is a narrow panel 40 and these panels 40 are connected to the rib structures A in substantially the same manner as the panels 8 are

35 connected to the ribs A (see Figure 2.) In respect to the rib structures B, the panels 40 are bent inwardly and backwardly as at 41 to define channels into which engage the clip strip 42 which also embrace the outturned outer edge portions 43 of the external channel members 44. The clip 42 embraces the inside of the channel member 44 and against the clip strip 42 bears the lateral wing member 45 of the intermediate channel member 46, and against the wing 45 engages the wing 47 of the internal channel member 48. Along their opposite edges, the channeled members 44, 46 and 48 have outstanding flanges 49, 50 and 51 which are held in spaced relation due to the particular shapes of the channeled members and these are held together by

50 the aforementioned means and the screws 52 which are of the same type as the screws 21. Thus slideways 53 and 54 are defined in each of the rib structures B for receiving the offset edge portions of the upper and lower slide doors 38 and 39. The lower slide door 39 has the outstanding flange structure 55 which can abut the outstanding flange 56 at the upper edge of the apron 57, this apron 57 having its end portions 58 interlocked with the lower portions of the rib structures B—B.

The upper edge of the slide door 39 is bent upwardly and against itself as at 58 for the purpose of reinforcement, and is equipped with a handle structure 59.

The upper door 38 has a handle structure 60 adjacent its lower portion and its lower edge is bent outwardly and backwardly and against itself as at 61 to define a reinforcing flange.

The upper edge of the slide door 38 is slightly offset as at 62 and has its edge portion fed backwardly against itself for reinforcement as at 63.

As can be seen in Figure 9, at the lower edge of the sector 8a an angle member 64 is provided over the top flange of which is bent the lower edge portion of the sector 8a as at 65.

While the foregoing specification sets forth the invention in specific terms, it is to be understood that numerous changes in the shape, size and materials may be resorted to without departing 15 from the spirit and scope of the invention as claimed hereinafter.

Having described the invention, what is claimed as new is:

1. In a roof for silos, a pair of upwardly tapering and outwardly bowed plate-like sections arranged in adjoining relation with side edges confronting and spaced apart, said side edges being inturned and forming grooves extending along the same, and means to secure said sections together comprising a pair of strip-like clips having side edges bent upon themselves to provide tongues slidably interfitting with said grooves, and a pair of channel type tie members extending between said sections in nested spaced relation and slidably interlocking with said clips, respectively, said members being secured together in clamping relation with respect to the edges of said sections and said clips. 20

2. In a roof structure for silos, a pair of upwardly tapering outwardly bowed plate-like sections arranged in adjoining relation with side edges confronting and spaced apart, said side edges being turned back upon themselves to provide grooves extending along the same, a pair of strip-like clips having side edges bent upon themselves to provide tongues slidably interfitting with said grooves, a pair of tie members of channel type extending along said edge of each section and secured in clamping relation to the clip of said edge, said pairs of tie members being connected together and constructed and arranged to provide door guideways for a sliding door, and a door slidably mounted in said guideways. 35

3. In a roof structure for silos, a pair of upwardly tapering plate-like sections arranged in adjoining relation with side edges confronting and spaced apart, said side edges being turned back upon themselves to provide grooves extending along the same, a pair of strip-like clips having side edges bent upon themselves to provide tongues slidably interfitting with said grooves, a pair of tie members of channel type extending along said edge of each section and secured in clamping relation to the clip of said edge, said pairs of tie members being connected together and constructed and arranged to provide door guideways for a sliding door, and a door slidably mounted in said guideways. 50

WILLIAM W. GURNEY. 65
